COURSE PLOTTING APPARATUS

Albert M. Patterson, Hutchinson, Kans.

Application March 13, 1944, Serial No. 526,299

18 Claims. (Cl. 35—40)

The main objects of this invention are:

First, to provide a course plotting apparatus which may be employed by aviators or by drivers of motor vehicles not only for plotting general course but in plotting a course from place to place on that general course.

Second, to provide an apparatus of this character which is very easily and quickly manipulated or adjusted for the plotting of a particular course.

Third, to provide a course plotting apparatus which while relatively compact is adapted for plotting a relatively large area.

Objects relating to details and economies of the invention will appear from the description to follow. The invention is defined in the claims.

A preferred embodiment of the invention is illustrated in the accompanying drawings, in which:

Fig. 1 is a fragmentary view of one side of the apparatus which for convenience may be designated as the front side, disclosing a map of the United States and a course platted thereon from Washington, D. C. to Albuquerque, New Mexico.

Fig. 1—A is a perspective view of the other or rear side of the apparatus with a section of the course from Washington to Albuquerque plotted, the section being from Washington, D. C. to Carrollton, Kentucky.

Fig. 2 is an enlarged front plan view partially broken away and partially in section.

Fig. 3 is an enlarged fragmentary section illustrating the relationship of one of the strand guides and the coacting actuator of one of a pair of actuators.

Fig. 3—A is an enlarged fragmentary section showing the mounting means for the other actuator of the pair and the relatively fixed anchoring means for one end of the plotting strand.

Fig. 4 is a vertical section on a line corresponding to line 4—4 of Fig. 2, certain parts being shown in full lines.

Fig. 5 is an enlarged view of the sectional map strips adjusted to bring certain complementary sections into register or complementing relation.

Fig. 6 is an enlarged fragmentary view mainly in section on line 6—6 of Fig. 4.

Fig. 7 is an enlarged fragmentary view in section on line 7—7 of Fig. 3.

The course plotting apparatus illustrated in the accompanying drawings is adapted or set up for plotting courses in the United States. It will be understood, however, that the device is adapted for any selected area with the condition

that the maps used are scaled for the apparatus or, otherwise stated, that the apparatus is scaled for the particular maps.

The embodiment of my invention illustrated 5 comprises a rectangular frame made up of side pieces 1 and 2 and top and bottom pieces 3 and 4 suitably joined together. This frame is provided with a transparent front panel 5 and transparent rear panel 6 which desirably may be of Pliofilm or similar material. These panels cover the windows 7 and 8.

It will be understood that I use the terms "front" and "rear" as matters of convenience in description and either side may be designated as 15 front and the other as rear.

The map A which I designated as an area map is mounted within the casing to be exposed through the window 7. Sectional map strips B and C are provided, these map strips being of 20 considerable length and having thereon complementary sections of the area map, these sections being relatively enlarged as compared to the area map. Registering complementary sections of the sectional map strips are exposed through the window 8—for example, see Fig. 1—A. In Fig. 5 other complementary sections of the map strips are disposed in complementary relation. The front and rear transparent casing members overlie mask-like portions which constitute the windows.

The front and rear walls in the embodiment illustrated have graduations 9 associated therewith, these graduations having a series of consecutive numerals 10, the graduations beginning at 30 the center of the top of the windows and extending in clockwise direction around the windows, there being thirty-six of the numerals in the structure illustrated. The graduations correspond on both sides.

The sectional map strips are mounted on rollers 11 arranged in pairs on the shafts or spindles 12, the adjacent ends of the map strips on the rollers being spaced by the plates 13 which are set into the frame. The rollers are provided with flanges 14 at their outer ends, these flanges having jaw portions 15 with which the jaws on the inner ends of the adjusting sleeves 16 engage. These adjusting sleeves or members are rotatably mounted on the spindle 12 and are provided with 40 finger pieces 17 at their outer ends. Spring pressed friction blocks 18 coacting with the outer flanges or rollers, as shown in Fig. 6, hold them in their adjusted position. With this arrangement, the sectional map strips may be adjusted 45 in either direction to bring the desired comple-

mentary map sections into complementary relation.

The complementary sections of the map strips are provided with registering indicia 19 such as 3A, 4A, as shown in Fig. 1—A and 1D, 2D, 3D, 4D and 5D as shown in Fig. 5. Letters and numerals are used in order to more easily designate the complementary series or complementary sections.

The casing frame members are provided with angled channels 20 and 21 arranged in oppositely disposed pairs. These channels have longitudinal slots 22 at the front thereof, the channels being normally covered by the window framing mats.

The course indicating or plotting strands 23 and 24 are supported for adjustment across the face of the map by means of guides 25 and 26. As these guides and the actuators therefor and other details of their mounting and manipulation of the strands are duplicated for the opposite sides of the apparatus, a description of one will suffice.

The guides 25 are translated around the frame of the casing by means of helically coiled actuators 27 and 28. These are in the form of helically coiled springs. The actuator 27 is rotatably mounted at one end by means of the flanged bushing 29 which is rotatable on the journal 30 of the support member 31 disposed at the upper right-hand corner of the frame, as viewed in Fig. 2. The other end of the actuator 27 is provided with a finger piece 32 by means of which the actuator may be rotated within the channel thereby moving the guide member longitudinally of the actuator, the guide member having a portion extending between the coils, as is shown in Figs. 2 and 3.

The support 31 for the bushing 29 for the actuator 27, see lower left-hand corner of the structure as viewed in Fig. 2 and the right of Fig. 3, is provided with a bore of sufficient diameter to permit the strand 23 to pass freely therethrough and through the guide 33 to the tension or take-up spool 34. This take-up roller has a tension spring 35 corresponding to the tension spring 35 for the second take-up roller or spool 34 for the second plotting strand 24. The relatively fixed ends of the strands are secured to the support members 31, see Fig. 3-A.

With this arrangement, by manipulating the finger pieces 32, the guide members are translated longitudinally of the actuators and thereby adjusted across the map to indicate a course between two selected or predetermined places on the area map—for example, in the illustration shown in Fig. 1, the course between Washington, D. C., and Albuquerque, New Mexico. It will be noted that the right-hand end of the strand is slightly below the numeral 9 and the left-hand end slightly above the numeral 26.

The strand is preferably provided with distance indicating indicia as 36, the light spots indicating the indicia. This is scaled according to the area map. The strand 24 has distance indicia 37 scaled according to the sectional map.

With the parts thus arranged, the plotting strand may be adjusted to indicate the course between any two places on the area map. When this has been done, the operator adjusts the second strand 24 to a position corresponding to the adjustment of the strand 23 with one slightly below the numeral 9 and the other slightly above the numeral 26. The sectional map strip B is then adjusted to bring the starting point, Wash-

ington, D. C., into approximate register with the sectional course indicating strand. The sectional map strip C is then adjusted to bring its indicia 3A, 4A into register with the indicia 3A, 4A on the strip B. It thus is indicated that the course lies through Elkins and Spencer, West Virginia, Portsmouth, Ohio, and Carrollton, Kentucky, these being the points indicated for illustration purposes on the sectional map. When Carrollton, Kentucky is reached, the sectional strip B is then readjusted to bring the next city or landmark west of Carrollton indicated on the course line 23 on the area map A into registering or approximate register with the course strand 24 and the sectional map C is adjusted until the indicia 19 at the right hand edge of strip C registers with the corresponding indicia along the left hand edge of strip B, in which position the geographic areas of strip C register exactly with those of strip B, just as those areas register on area map A. It will be understood that each of the sectional map strips B and C may consist of one complete map of the United States cut in strips and secured end to end, proceeding from east to west or vice versa. This manipulation is repeated as the course is followed until destination is reached. In a complete crossing of the United States, several of the series of map sections are employed. With this arrangement, any course within the United States or within the area to be traversed and properly mapped on the area map and on the sectional maps may be quickly and effectively plotted and easily followed.

I have illustrated and described an embodiment of my invention which I have found to be very practical. I have not attempted to illustrate or describe other adaptations or embodiments for various areas, for example, or in structural details for particular adaptations as it is believed that this disclosure will enable those skilled in the art to embody or adapt my invention as may be desired.

Having thus described my invention, what I claim as new and desire to secure by Letters Patent, is:

1. In a course plotting apparatus, the combination with a casing having windows on opposite sides thereof, there being correspondingly positioned graduations and associated numerals associated with each window, the numerals being consecutive around the windows and beginning centrally of the tops thereof, of an area map exposed through one of said windows, sectional map strips disposed edge to edge for exposure of selected portions thereof through the other window, pairs of supporting rollers for said sectional map strips mounted within said casing and provided with finger pieces whereby the map strips may be independently adjusted, each of said sectional map strips having thereon a series of complementary sections of said area map, said map strips each having a corresponding series of registerable positioning indicia facilitating the positioning sections of the maps in complementing relation, pairs of oppositely disposed angular channels within said casing having longitudinal slots in the front sides thereof, helically coiled strand guide actuators disposed in said channels for rotation therein, said actuators at one of the ends of each thereof being rotatably mounted at diagonally opposite corners of said casing and provided with finger pieces at their other ends whereby they may be independently rotated, pairs of course indicating

strand guides engaged with the coils of said actuators to project through the slot-like openings of said channels whereby upon rotation of the actuators the guides are moved longitudinally of the actuators, course indicating strands supported by said guides for adjustment across the windows and the maps exposed therein, said strands being guided to and from the interiors of said actuators by said guides, one end of each strand being relatively fixed at the rotatably mounted end of one of said actuators of a pair and extending longitudinally interiorly of said actuator from said end to the strand guide engaging said actuator, the other being relatively free, said strands having distance indicia thereon corresponding in scale to the scale of the maps with which they are associated, there being a guide for the relatively free end of the strand at the corresponding rotatably mounted end of the other actuator of the pair, and spring wind take-up spools for the free ends of said strands mounted within said casing.

2. In a course plotting apparatus, the combination with a casing having windows, there being correspondingly positioned indicia around the windows, of an area map exposed through one of said windows, sectional map strips disposed edge to edge for exposure of selected portions thereof through the other window, pairs of supporting rollers for said sectional map strips mounted within said casing and provided with finger pieces whereby the map strips may be independently adjusted, each of said sectional map strips having thereon a series of complementary sections of said area map, said map strips each having a corresponding series of registerable positions of the maps in complementing relation, pairs of oppositely disposed angular channels within said casing having longitudinal slots in the front sides thereof, helically coiled strand guide actuators disposed in said channels for rotation therein, said actuators at one of the ends of each thereof being rotatably mounted at diagonally opposite corners of said casing and provided with finger pieces at their other ends whereby they may be independently rotated, pairs of course indicating strand guides engaged with the coils of said actuators to project through the slot-like openings of said channels whereby upon rotation of the actuators the guides are moved longitudinally of the actuators, course indicating strands supported by said guides for adjustment across the windows and the maps exposed therein, said strands being guided to and from the interiors of said actuators by said guides, one end of each strand being relatively fixed at the rotatably mounted end of one of said actuators of a pair and extending longitudinally interiorly of said actuator from said end to the strand guide engaging said actuator, the other being relatively free, there being a guide for the relatively free end of the strand at the corresponding rotatably mounted end of the other actuator of the pair, and spring wind take-up spools for the free ends of said strands mounted within said casing.

3. In a course plotting apparatus, the combination with a casing having windows, there being correspondingly positioned indicia associated with each window, of an area map exposed through one of said windows, adjustably supported sectional map strips disposed edge to edge for exposure of selected portions thereof through the other window, pairs of oppositely disposed angular channels within said casing having longitudinal slots

in the front sides thereof, helically coiled strand guide actuators disposed in said channels for rotation therein, said actuators at one of the ends of each thereof being rotatably mounted at diagonally opposite corners of said casing and provided with finger pieces at their other ends whereby they may be independently rotated, pairs of course indicating strand guides engaged with the coils of said actuators to project through the slot-like openings of said channels whereby upon rotation of the actuators the guides are moved longitudinally of the actuators, course indicating strands supported by said guides for adjustment across the windows, one end of each strand being relatively fixed at the rotatably mounted end of one of said actuators of a pair, the other being relatively free, said strands having distance indicia thereon corresponding in scale to the scale of the maps with which they are associated, there being a guide for the relatively free end of the strand at the corresponding rotatably mounted end of the other actuator of the pair, and resilient take-up means for the free ends of said strands.

25 4. In a course plotting apparatus, the combination with a casing having windows, there being correspondingly positioned indicia associated with each window, of an area map exposed through one of said windows, adjustably supported sectional map strips disposed edge to edge for exposure of selected portions thereof through the other window, pairs of oppositely disposed angular channels within said casing having longitudinal slots in the front sides thereof, helically coiled strand guide actuators disposed in said channels for rotation therein, said actuators at one of the ends of each thereof being rotatably mounted at diagonally opposite corners of said casing and provided with finger pieces at their other ends whereby they may be independently rotated, pairs of course indicating strand guides engaged with the coils of said actuators to project through the slot-like openings of said channels whereby upon rotation of the actuators the guides are moved longitudinally of the actuators, and course indicating strands supported by said guides for adjustment across the windows.

50 5. In a course plotting apparatus, the combination with a casing having windows, there being correspondingly positioned graduations and associated numerals associated with each window, of an area map exposed through one of said windows, adjustably supported sectional map strips disposed edge to edge for exposure of selected portions thereof through the other window, each of said sectional map strips having thereon a series of complementary sections of said map area, pairs of helically coiled rotatably supported strand guide actuators, pairs of course indicating strand guides engaged with the coils of said actuators to be translated thereby upon rotation of the actuators, course indicating strands supported by said guides for adjustment across the windows and the maps exposed therein and having distance indicia thereon corresponding in scale to the scale of the maps with which they are associated, said strands being guided to and from the interiors of said actuators by said guides, one end of each strand being relatively fixed and extending longitudinally interiorly of said actuator from said end to the strand guide engaging said actuator, the other being relatively free, and spring wind take-up spools for the free ends of said strands.

6. In a course plotting apparatus, the combination with a casing having windows, there being correspondingly positioned graduations and associated numerals associated with each window, of an area map exposed through one of said windows, adjustably supported sectional map strips disposed edge to edge for exposure of selected portions thereof through the other window, each of said sectional map strips having thereon a series of complementary sections of said area map, pairs of helical rotatably supported strand guide actuators, pairs of course indicating strand guides engaged with the actuators to be translated thereby upon rotation of the actuators, and course indicating strands supported by said guides for adjustment across the windows and the maps exposed therein. 10
7. In a course plotting apparatus, the combination with a casing having windows, there being correspondingly positioned indicia associated with the windows, of an area map exposed through one of said windows, adjustably supported sectional map strips disposed edge to edge for exposure of selected portions thereof through the other window, each of said sectional map strips having thereon a series of complementary sections of said area map, pairs of helical rotatably supported strand guide actuators, pairs of course indicating strand guides engaged with the actuators to be translated thereby upon rotation of the actuators, course indicating strands adjustably supported by said guides for adjustment across the windows and the maps exposed therein, one end of each strand being relatively fixed, the other being relatively free, and take-up means for the free ends of said strands. 20
8. In a course plotting apparatus, the combination with a casing having windows, there being correspondingly positioned indicia associated with the windows, of an area map exposed through one of said windows, adjustably supported sectional map strips disposed edge to edge for exposure of selected portions thereof through the other window, each of said sectional map strips having thereon a series of complementary sections of said area map, pairs of helical rotatably supported strand guide actuators, pairs of course indicating strand guides engaged with the actuators to be translated thereby upon rotation of the actuators, course indicating strands adjustably supported by said guides for adjustment across the windows and the maps exposed therein, and take-up means for the free ends of said strands. 40
9. In a course plotting apparatus, the combination with a map, of a pair of helical rotatably supported strand guide actuators mounted at the edges of the map in opposed angular relation, course indicating strand guides engaged with the said actuators to be translated thereby upon rotation of the actuators, a course indicating strand rove through said guides for adjustment thereby across the map, one end of each strand being relatively fixed and the other relatively free, and a spring wind take-up spool for the free end of said strand. 50
10. In a course plotting apparatus, the combination with a map, of a pair of helical rotatably supported strand guide actuators mounted at the edges of the map in opposed angular relation, course indicating strand guides engaged with the said actuators to be translated thereby upon rotation of the actuators, and a course indicating strand carried by said guides for adjustment thereby across the map. 60
11. In a course plotting apparatus, the combination with a casing having windows, there being correspondingly positioned indicia associated with each window, an area map exposed through one of said windows, adjustable sectional map strips disposed edge to edge for exposure of complementary portions thereof through the other window, said sectional map strips having thereon a series of complementary sections of said area map, said map strips having registerable indicia to facilitate positioning of complementary map sections in complementing relation, actuators disposed angularly in opposed relation to substantially embrace the window, strand guides engaged with the actuators to be translated along two sides of the windows, and course indicating strands engaged with said guides and having distance indicia thereon corresponding with the scale of the maps with which they are associated, said strands being disposed across the windows for adjustment across the maps disclosed therein, one end of the strands being relatively fixed. 15
12. In a course plotting apparatus, the combination with a casing having windows, there being correspondingly positioned indicia associated with each window, an area map exposed through one of said windows, adjustable sectional map strips disposed edge to edge for exposure of complementary portions thereof through the other window, said sectional map strips having thereon a series of complementary sections of said area map, actuators disposed angularly in opposed relation to substantially embrace the window, strand guides engaged with the actuators to be translated along two sides of the windows, and course indicating strands engaged with said guides. 30
13. In a course plotting apparatus, the combination with a casing having windows, an area map exposed through one of said windows, adjustably mounted sectional map strips disposed edge to edge for exposure of complementary portions thereof through the other window, said map strips having thereon a series of complementary sections of said area map, said map strips having a corresponding series of registerable indicia to facilitate the positioning of the complementary map sections in complementing relation, course indicating strands disposed across said windows to overlie the maps exposed therein, said strands having distance indicia thereon corresponding to the scale of the maps with which they are associated, said windows having correspondingly positioned indicia associated therewith, means for independently adjusting the ends of the reaches of the course indicating strands comprising flexible rotatably mounted actuators disposed in angular relation and in opposed pairs, each actuator extending along two sides of the window, and strand guide members operatively associated with said actuators to be translated thereby upon the rotation of the actuators, said strands being roved through said guides and being anchored at one end and provided with automatic take-ups at their free ends. 55
14. In a course plotting apparatus, the combination with a casing having windows, an area map exposed through one of said windows, adjustably mounted sectional map strips disposed edge to edge for exposure of complementary portions thereof through the other window, said map strips having thereon a series of complementary sections of said area map, said map strips having a corresponding series of registerable indicia to facilitate the positioning of the complementary map sections in complementing relation, actuators disposed angularly in opposed relation to substantially embrace the window, strand guides engaged with the actuators to be translated along two sides of the windows, and course indicating strands engaged with said guides. 70
- 75

mental map sections in complementing relation, course indicating strands disposed across said windows to overlie the maps exposed therein, said strands having distance indicia thereon corresponding to the scale of the maps with which they are associated, said windows having correspondingly positioned indicia associated therewith, means for independently adjusting the ends of the reaches of the course indicating strands comprising flexible rotatably mounted actuators disposed in angular relation and in opposed pairs, each actuator extending along two sides of the window, and strand guide members operatively associated with said actuators to be translated thereby upon the rotation of the actuators.

15. In a course plotting apparatus, the combination of a main area map, auxiliary map members disposed edge to edge for adjustment relative to each other and for exposure of complementary portions thereof, said auxiliary map members having thereon a series of complementary sections of the main map, course indicating strands disposed across said maps, there being correspondingly positioned indicia associated with the edges of the main and auxiliary maps, and means for independently adjusting the ends of the reaches of the course indicating strands extending across the maps along two sides of the maps.

16. In a course plotting apparatus, the combi- 30

nation of a main area map, auxiliary map members disposed edge to edge for adjustment relative to each other and for exposure of complementary portions thereof, said auxiliary map members having thereon a series of complementary sections of the main map, course indicating strands disposed across said maps, and means for independently adjusting the ends of the reaches of the course indicating strands extending across the maps along two sides of the maps.

17. In a course plotting apparatus, the combination of a map, a course indicating strand having a reach thereof disposed across the map, and means for independently adjusting the ends of the reaches of the strands extending across the map, each end being adjustable along two sides of the map.

18. In a course plotting apparatus, the combination of a casing having windows, there being correspondingly positioned indicia associated with each window, an area map exposed through one of said windows, an adjustable auxiliary map member having thereon enlarged portions of the area map, course indicating strands extending across the windows and the maps exposed therein, and means for independently adjusting the ends of the reaches of said strands so extending across the exposed maps.

ALBERT M. PATTERSON.
